UNITED STATES PATENT OFFICE.

JOHN S. WINCRANTZ, OF PITTSBURG, PENNSYLVANIA.

TELEPHONE-TRANSMITTER ATTACHMENT.

No. 908,356.

Specification of Letters Patent. Patented Jan. 12, 1909.

Application filed August 12, 1908. Serial No. 448,259.

To all whom it may concern:

Be it known that I, JOHN S. WINCRANTZ, a citizen of the United States, residing at Pittsburgh, in the county of Allegheny and State of Pennsylvania, have invented certain new and useful Improvements in Telephone-Transmitter Attachments; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to telephone-transmitter attachments, and has for its object to render the transmitter temporarily inoperative during service.

It is frequently desired by those using a telephone to momentarily cease using the telephone, during conversation thereover, to answer or ask questions of those near at hand, relative to the conversation referred to, upon which occasions it has been the custom to place the palm of the unoccupied hand over the mouth piece of the transmitter, in order to prevent the party at the other end of the line hearing such questions, but it has been found that this placing of the hand upon the mouth piece is not effective, owing to the hand being a conductor of sound vibrations like that of other portions of the body, therefore the object of my invention is to provide a simple and effective means of overcoming the difficulty.

In the accompanying drawings, forming a part of this specification in which the invention is fully described, I have illustrated the application of my invention to the transmitter of a telephone, wherein—

Figure 1, is a longitudinal sectional view through a mouth piece, associated with the transmitter diaphragm, and my improved attachment. Fig. 2, is a transverse sectional view of the left-hand portion of the same, on the line X. X. of Fig. 1, and Fig. 3, is a similar view of that portion on the right of said section, similar detail parts of said device throughout the views being designated by like numerals of reference.

The invention comprises, a cylindrical member formed of the two sections 1 and 2, threadably connected at one end to and forming an extension to the usual mouth piece 3, the opposite end being threadably

connected to the transmitter casing (not shown) inclosing the usual diaphragm 5, said extension being provided with perforated heads 6 and 7, the latter having a centrally disposed and shouldered opening 8 into which is loosely fitted a plunger 9 having a cup-shaped head upon the end within the shouldered portion of the opening and a rounded one at the other, which plunger is held, by a spiral spring 8' surrounding the same, in engagement with a lever 10 extending up through an elongated opening 11, in the under side of and pivotally secured between lugs 12 in the aforesaid section 1, said section being further provided with a perforated soft rubber disk 13, within its outer end, and a sanitary gauze disk 14 adjacent the inner surface of the aforesaid head 7; an opening 15 being provided in the upper portion of the said section 1 for injecting the disinfectant fluid upon said gauze.

In practice, when it is desired to temporarily cut out the transmitter-line during conversation, the operator simply presses forward the lever 10, which operation causes the plunger 9 to move forward, bringing the cup-shaped head thereof into engagement with the soft rubber disk 13, forcing the same into contact with the projecting head 16 upon the diaphragm of the transmitter, holding the said diaphragm under tension, and as the soft rubber member is a non-conductor of vibration the transmission of sound waves is effectually prevented. Thus the transmitter line may be cut out of service as long as the lever is held in abnormal position.

Having thus fully shown and described my invention, what I claim and desire to secure by Letters Patent is—

1. In a device of the character set forth, an extension connected to and between the mouth piece and transmitter casing, a lever projecting from and supported in said extension, a non-vibrating member arranged in said extension adjacent the transmitter diaphragm, and a member interposed between the same and lever, whereby said non-vibrating member may be forced into engagement with the diaphragm by said lever to prevent said diaphragm transmitting sound waves.

2. In a device of the character set forth, an extension connected to and between the mouth piece and transmitter casing and having perforated heads therein, a non-vibrating member arranged therein between one of said

heads and the transmitter diaphragm, a lever pivotally arranged in said extension between the perforated heads the free end of which extends through the extension, and a member interposed between said lever and non-vibrating member, whereby said non-vibrating member may be forced into engagement with the diaphragm by the lever to prevent said diaphragm transmitting sound waves.

3. In a device of the character set forth, an extension connected to and between the mouth piece and transmitter casing and having perforated heads therein, a non-vibrating and perforated disk arranged therein between one of said heads and the transmitter

diaphragm, a lever pivotally arranged in said extension between said heads and having its free end extending through a slot in said extension, and a plunger arranged in the head 20 between the lever and non-vibrating disk and provided with means to maintain its engagement with the lever, adapted to act as a means to force the non-vibrating disk into engagement with the transmitter diaphragm 25 by the movement of said lever.

In testimony whereof, I affix my signature, in presence of two witnesses.

JOHN S. WINCRANTZ.
